UNITED STATES PATENT OFFICE.

GUSTAVUS W. INGALLS, OF CONCORD, NEW HAMPSHIRE.

IMPROVEMENT IN REED-PLATES FOR MELODEONS, &c.

Specification forming part of Letters Patent No. **59,027**, dated October 23, 1866.

To all whom it may concern:

Be it known that I, GUSTAVUS W. INGALLS, of Concord, in the county of Merrimack and State of New Hampshire, have invented a new and useful Improvement in Reed Socket-Plates for Melodeons or other musical instruments of like character; and I do hereby declare the same to be fully described in the following specification and represented in the accompanying drawings, of which—

Figure 1 is a top view, Fig. 2 a transverse section, and Fig. 3 a longitudinal section, of a reed socket-plate made in accordance with my invention, the drawings being made on a scale very much greater than that of an ordinary socket-plate.

In the common method of punching out the openings of reed-plates a burr or rough edge is left, which produces during vibration of the reed more or less harshness of tone. The object of my invention is to avoid this, and in carrying it out I punch the plate by means of a punch or die, so as to form the opening, and I subsequently form in that side of the plate which is opposite to that at which the punch first entered it a mouth to the opening.

In the drawings, A is the plate, *a* the reed-opening, and *b* its mouth. In this way the edges *c c* and ends of the reed-opening *a* become rounded, the same being in consequence of the condensation of the metal before the part to be removed from it may be broken from the rest of the plate by the punch. This saves all dressing of the edges or facing of the plate in order to separate any burr from them, and causes the sound of the reed to be smooth and even. It also saves much labor in “voicing” the reed.

The mouth may be formed or made by a rotary cutter to cut into the plate on that side of it from which the blank or piece of metal leaves it when forced out of it by the punch.

I claim—

The improved reed socket-plate made substantially as described—viz., by punching it through in one direction and forming the mouth on that side which is opposite to that surface at which the punch is made to enter the metal.

GUSTAVUS W. INGALLS.
